UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT.

TOY GEAR BOX.

Application filed February 25, 1921. Serial No. 447,820.

To all whom it may concern:

Be it known that I, ALFRED C. GILBERT, a citizen of the United States, residing in New Haven, county of New Haven, and State of Connecticut, have invented certain new and useful Improvements in Toy Gear Boxes, of which the following is a full, clear, and exact description.

This invention relates to toy gear boxes and more particularly to a frame construction such as is shown in my Patent No. 1,219,452, adapted to be used in connection with toy motors or the like to support the shafts and gearing in operative driving relation to each other and to the driving gear upon the motor shaft. The gear box may also be constructed to removably support a switch and other accessories useful in connection with the operation of a toy motor and associated mechanical devices operated thereby.

One object of the invention is to provide a toy gear box with side plates of such novel construction that a plurality of shafts may be adjustably supported by the plates in operative relation to each other and to the motor used in connection therewith.

A further object of the invention is the provision of means whereby the gear shafts may be supported for sliding adjustment so that very fine adjustments of shafts may be made to prevent either the binding of the gears when the shafts are too close or loose fitting of the gears when the shafts are too far apart.

A still further object of the invention is to provide a gear box in which gear shafts may be adjustably supported, and cooperating means which will enable the shafts to be adjusted without the necessity of removing them from their bearings.

In the accompanying drawings:

Fig. 1 is a front elevational view of a toy gear box embodying the principles of my invention;

Fig. 2 is a side view of the same;

Fig. 3 is a top plan view of the structure shown in Fig. 1;

Fig. 4 is a sectional view on line 4-4 of Fig. 2;

Fig. 5 is a view similar to Fig. 2, but showing the gear box and motor attached to a motor base;

Fig. 6 is a sectional view on line 6-6

of Fig. 5 showing the construction of the motor base; and

Fig. 7 is a detail view of one of the bearing straps used with the side plate of the gear box.

The gear box constructed in accordance with the principles of my invention preferably consists of the two side plates 10 and 11, which are substantially identical, so that it will be necessary to describe only one of these plates. The plate at 10, for example, consists of a main body plate 12, substantially rectangular in shape, which is provided with two side flanges 13 and 14, and a bottom flange 15, which extend substantially at right angles to the plane of the body plate 12. The flanges 13, 14 and 15 may be provided with perforations 13^a, 14^a and 15^a, the purpose of which will be hereinafter described.

To suitably support the various shafts in the side plates of the gear box, the same are provided with a plurality of elongated slots 16, as shown more especially in Figs. 2, 4 and 5. As shown, these slots are substantially parallel with each other and extend generally longitudinally of the side plates of the gear box, but the arrangement and number of the slots may be varied without departing from the principles of the invention. The plates are shown provided with five of the slots 16, which I have found to be a convenient number to provide a proper spacing of the same without weakening the side plates to any material degree. The slots are preferably arranged in the same way in each of the plates, so that when the gear box is made up by mounting the two plates in opposed relation to each other, the slots will be disposed in alignment with each other.

To cooperate with the slots and form bearings for the shafts, I have provided the bearing straps 17, which, as shown in Figs. 4 and 5, are adapted to be applied to the plates 12 and 13, so that they extend generally transversely of the slots 16. These straps are in turn slotted, as shown at 18, which slots may extend almost the entire length of the bearing strap, but preferably the straps are provided with a plurality of shorter slots, as shown in the drawings. These slots extend longitudinally of the straps and cooperate with the slots 16, so

that the point of intersection of the two slots will form a shaft bearing. The straps may also be provided with perforations 19, as shown, to cooperate with certain of the slots 16, when the length of the strap would make the provision of such a perforation more expedient than the provision of another slot. As shown in the drawings, each of these straps is provided with two of the slots 18 and a perforation 19 disposed between them. Such an arrangement is found to be very suitable in cooperation with the five slots 16 in the side plate of the gear box. Screws 20 are passed through certain of the shaft bearings formed by the crossing of the two slots to secure the straps in position. When the screws are disposed at the two ends of the straps 17, it is seen that the straps will be securely held against 20 longitudinal movement on the plates.

Shafts 21 and 22 are shown supported in the bearings formed by the straps 17 and the side plates 12 and the first of these shafts carries a pulley 24 on one end and a gear 23 upon the other which is in mesh with a gear 25 upon one end of the shaft 22. The shaft 22 carries a gear 26 upon its other end, which is in mesh with a gear 27 secured upon a motor shaft 28. The gears 23, 25, 26 and 27 are provided with gear hubs 29, 30, 32 and 33, respectively, which are secured to the gears and are non-rotatably mounted upon the shafts by set screws 34. To prevent longitudinal movement of the shafts relative to the gear box, the same are provided with the clips 35, which are secured to the shafts by the set screws 36. These clips are, as shown, preferably mounted on the shafts just within the side plates and 40 closely adjacent to the plates so they will hold the shafts in position. It is seen that with this arrangement, the gears may be mounted in any position upon the shafts, so that the hubs 29, 30, and 32 are not required to bear against the straps 17 in order to hold the shafts in position. The gears can then be brought into proper vertical alignment with each other, so that the teeth will properly mesh regardless of the disposition 50 of the gear collars.

The two side plates 10 and 11 may be mounted upon the frame of a motor 36, as shown in Fig. 1. The motor here shown may be of the same type, as shown in my prior patent, referred to above, so that further description is believed to be unnecessary, except that it may be said that the frame plates 37 and 38 of the motor are provided with bottom flanges 39 and 40, which are secured by bolts to the bottom flanges 15 of the side plates. The shaft 28 referred to above is shown as the shaft of this motor.

The side flanges 13 and 14 of the two plates 10 and 11 are adapted to support a

switch plate 41 upon which may be mounted a reversing switch (not shown) which is controlled by the switch lever 42. The switch plate carries the binding posts 43, which will, when the switch is in use, be suitably connected with the binding posts 44 upon the motor frame. Such a structure is shown in Figs. 1 and 2 where the switch plate is suitably mounted upon the side plates which are in turn supported upon the frame of the motor. It is seen that the gear box will support the shafts in operative relation to each other and to the motor shaft and the reducing gearing which is shown mounted upon the shafts 21 and 22 will 80 reduce the speed of the motor so that various contrivances can be driven from the pulley 24.

As shown in Fig. 5, the gear box and motor may be suitably mounted, if desired, 85 upon a motor base 45, which will carry the switch base 41, which in Figs. 1 and 2 was shown mounted upon the gear box. The motor base is connected to the gear box structure, as described in my prior patent, 90 above referred to, by the bolts 46, which pass through the motor base and through the bottom flanges 15 upon the side plates. The switch used in connection with the structure shown in Figs. 1 and 5 can be of any 95 preferred construction, for instance, similar to the switches shown in my Patents Nos. 1,307,094, granted June 17, 1919, and 1,323,045, granted November 25, 1919.

The side plates are also provided with the 100 openings 47 and 48, which are in the nature of clearance openings for certain portions of the motor frame and shaft which project therethrough.

It will be obvious from the foregoing 105 description that the gear shafts 21 and 22, when mounted in accordance with the principles of my invention, will be capable of sliding adjustment within the slots 16. Such adjustment is accomplished by loosening the 110 bolts 20 and sliding either one or both ends of the straps to the desired position in the slots and then securing the bolts in position again by tightening the nuts thereon. This will provide for a very fine and nice 115 adjustment of the shafts, so that the gears may be supported in proper relation to each other to prevent any binding of the gears or to prevent any looseness of play between the teeth. This adjustment of the gears, it 120 will be seen, may be accomplished without the removal of the shaft from the bearings, which will be found to be very convenient and which could not be accomplished by gear plates which have been used heretofore. 125

What I claim is:

1. In a device of the character described, a gear box comprising spaced side plates, each of said plates being provided with a plurality of suitably disposed elongated

bearing slots and side flanges on the plates between which the gears may be housed.

2. As an article of manufacture, a side plate for gear boxes or the like provided with elongated bearing slots adapted to receive and adjustably support one end of a shaft, and having edge flanges adapted to extend generally at right angles to the plane of the plate.

3. The combination with a toy motor of a pair of plates connected thereto, said plates being extended beyond said motor and said extended portion having elongated bearing slots for mounting a shaft or shafts.

4. A side plate for toy gear boxes provided with an elongated slot, a bearing strap applied to said plate and also provided with a slot, said slots cooperating to form a shaft bearing.

5. A side plate for toy gear boxes provided with an elongated slot, and a bearing strap, provided with an opening, rigidly secured to said plate to support, within said opening, a shaft extending through said slot.

6. A side plate for toy gear boxes provided with an elongated slot, and a bearing strap, also provided with a slot, applied to the plate to extend generally transversely thereof, said slots intersecting to form a shaft bearing.

7. A side plate for toy gear boxes provided with an elongated slot and a bearing strap, also provided with a slot, adjustably applied to the plate to extend generally

transversely thereof, said slots intersecting to form an adjustable shaft bearing.

8. A side plate for toy gear boxes provided with a plurality of parallel slots, a bearing strap provided with a plurality of slots 40 adapted to be applied thereto with the slots of one member intersecting those of the other member, and fastening means passing through certain of said intersections to detachably interconnect said members, certain 45 other intersections forming shaft bearings.

9. The combination with a toy motor of gear box side plates detachably applied to opposite sides of the motor and a shaft journalled in said side plates, said journals being 50 capable of sliding adjustment.

10. The combination with a toy motor of a gear box having side members detachably applied to opposite sides of the motor, said members being provided with parallel elongated 55 slots for the purpose described.

11. The combination with a toy motor of transmission mechanism, including separate side plates detachably secured to the motor and provided with elongated parallel slots. 60

12. The combination with a toy electric motor having a frame of a gear box comprising side plates detachably applied to the opposite sides of the frame, said plates being provided with elongated slots and 65 means for slidably journalling a shaft in said slots.

In witness whereof, I have hereunto set my hand on the 18th day of February, 1921.

ALFRED C. GILBERT.
